UNITED STATES PATENT OFFICE.

CHARLES ZABEL, OF CORAOPOLIS, PENNSYLVANIA, ASSIGNEE TO McDOWELL MANUFACTURING COMPANY, OF MILLVALE, PENNSYLVANIA, A CORPORATION OF PENNSYLVANIA.

MECHANICAL RACING TOY.

Application filed June 29, 1925. Serial No. 40,146.

The invention is for an improvement in a mechanical racing toy.

The invention relates to toys of the general type disclosed in my co-pending application Serial No. 665,114 filed September 27, 1923.

In toys of this type, a gyratory motion is imparted to a suitable pan having one or more continuous tracks thereon. As the pan 10 gyrates, gravity propelled objects guided by the tracks are caused to travel around the tracks. Where there are two or more tracks, the appearance of a race is simulated and an extremely attractive 15 and fascinating toy is provided.

This invention is for an improved mechanical structure for toys of this type wherein the appearance and assembly of the toy is improved and facilitated, and 20 wherein a relatively compact and rugged construction is secured.

The invention has for a further object to provide a smooth-running toy of improved construction.

25 The invention may be readily understood by reference to the accompanying drawings, wherein,

Figure 1 is a perspective view of an assembled toy embodying the invention.

30 Figure 2 is a transverse section through the toy.

Figure 3 is a side elevation of a detail part of the toy.

35 Figure 4 is a top plan view of the base of the toy.

In the drawings, 5 designates a flanged base member of which 6 is the flange. At the center of the base member is a recess 5^a. At diametrically opposite points the 40 recess in the base extends out to the periphery of the base, such diametrically opposite radial depressions being designated 5^b.

Tightly fitted over the flange of the base, 45 and secured thereto is the wall 7 of a cylindrical housing having a top 8. In the side of the cylinder at diametrically opposite points and in line with recessed portions 5^b of the base, are vertical slots 9.

50 Secured to the underside of the top 8, or otherwise secured in the central housing, is the frame 10 of a spring motor 11. This motor drives a centrally located disk 12, having an eccentric opening therein, for the

purpose hereinafter described. The motor 55 has a key stem 13 projecting through the top of the housing, and to this stem is applied a winding key 14.

Contained within the housing below the motor is a transverse diametrically extending bar 15 whose opposite ends project through the respective slots in the housing. The end portions 15^a of this bar are rigidly secured to a dished sheet metal pan 16 having its central portion removed so that it 60 may fit over and surround the housing. This pan preferably has embossed annular ribs thereon dividing the pan or track member into a plurality of circular tracks 16^a, four such tracks being shown.

70 The central part of the bar 15 is pressed into a substantially inverted cone formation 15^b. Centered in this cone is a pin 17 whose lower end sets in a central hole 18 in the base member and whose upper end enters the eccentric opening in the motor driven centralized disk 12.

75 As thus arranged, the operation of the motor imparts a gyratory motion to the pin 17 whose one end is set in a central hole 80 and whose other end is eccentrically revolved by the disk 12. This movement of the pin imparts a corresponding rocking movement to bar 15, and the track member or pan 16 is thus caused to gyrate, or, in 85 other words, a progressive tilting motion is imparted to the pan which does not itself revolve. This tilting motion causes gravity propelled objects A to roll around the track in simulation of a race.

90 The base member is preferably of the peculiar shape described for the purpose of providing a flange on the base of sufficient width to permit the housing 7 to be firmly fitted and secured to the base while the 95 depressions allow for the proper tilting motion of the cross bar. The conical central portion of the bar provides a good bearing for the tilting bar, so that the tilting motion of the pan is smooth and continuous.

100 The toy as thus constructed is relatively lower than the toy shown in my said co-pending application, so that it requires less room for packing or display. The central housing not only compactly encloses and supports the operating parts, but its exterior 105 may be attractively lithographed to represent a grandstand or be otherwise decorated

to add to the attractive appearance of the toy.

In assembling the toy, the base may be the part last secured in place, so that the toy ⁵ can be easily assembled.

I claim as my invention:—

1. A mechanical toy including a central housing having openings in the side walls thereof, a transverse bar passing through ¹⁰ the housing and having a rocking support within the housing, a track member encircling the housing and secured to the opposite ends of the cross bar, and means in the housing and supported thereby for imparting a progressive tilting motion to the cross bar to correspondingly rock the track member, and a gravity propelled object on the track member.

2. A mechanical toy including a flanged ²⁰ base member, a housing member fitted over the flanged base member, a motor supported in the housing above the base member, a post pivoted on the base to be gyrated by the motor and operatively connected with ²⁵ the motor, a rocking beam secured to the post and having its ends projecting through the housing, a ring like track member surrounding the housing and secured to the

rocking beam, and a gravity propelled object on the track. ³⁰

3. A mechanical toy including a base member, a cylindrical housing carried on the base member, a motor supported in the upper part of the housing, a rocking beam in the housing having its opposite ends projecting ³⁵ therefrom, cooperating means on the motor and beam for imparting a gyratory motion to the beam, and a ring like pan surrounding the housing and secured to the opposite ends of said beam. ⁴⁰

4. A mechanical toy of the class described including a base member, a supporting structure carried thereby, a motor on the supporting structure above the base, a cross bar having an inverted cone-like central portion which rests on the base, a pin centered in the cone-like portion of the cross-bar with its lower end bearing in the base, the upper end of the pin being eccentrically connected with a revolving part of the motor, a dished ring-like track member carried by the cross beam and surrounding the motor supporting structure, and a gravity propelled object on the track member. ⁴⁵ ⁵⁰

In testimony whereof I affix my signature.
CHARLES ZABEL.
